United States Patent Office.

JOHN A. WRIGHT, OF KEENE, NEW HAMPSHIRE.

Letters Patent No. 78,428, dated June 30, 1868.

IMPROVED COMBINED MOP AND WRINGER.

The Schedule referred to in these Letters Patent and making part of the same.

TO ALL WHOM IT MAY CONCERN:

Be it known that I, JOHN A. WRIGHT, of Keene, in the county of Cheshire, and State of New Hampshire, have invented certain Improvements in Mops, of which the following is a full, clear, and exact description, reference being had to the accompanying drawings making part of this specification, in which—

Figure 1 is a perspective view of my improved mop.

Figure 2 is a horizontal longitudinal section through the centre of the same, with the handle locked in the position it occupies when the mop is ready for use.

Figure 3 is a vertical longitudinal central section, representing the handle in the position it occupies when the mop-cloth is being wrung out.

My invention consists in a sliding and revolving handle, provided with a device for locking it to the lower jaw in a position ready for use, and a device for catching the mop-cloth, so that it may be twisted around to be wrung, the upper jaw being of a convenient form to enable it to be grasped while being held or revolved in a contrary direction to the handle, thereby avoiding the necessity of applying the hands to wring the mop-cloth.

To enable others skilled in the art to understand and use my invention, I will proceed to describe the manner in which I have carried it out.

in the said drawings, A is the handle, to the upper or wooden portion a of which is screwed or otherwise secured the lower or metal portion b, which is of a circular form in transverse section, and is provided at its lower extremity with a recess, c, which extends to the outer surface of the portion b at points d d, placed diametrically opposite.

Within this recess c is pivoted, at e, two projecting lugs, f f, the office of which will presently be described. B is the upper jaw, and C the lower jaw, each of which is provided at its centre with a circular hole, for the reception of the portion b of the handle, which is thus free to slide and revolve therein. The opposite extremities of the lower jaw C are bent around at right angles, as shown, the bent portions g g passing through holes in the extremities of the upper jaw, and being provided with screw-threads, over which turn the nuts h h, by which means the ends of the mop-cloth are tightened or held firmly in place between the jaws, the bight of the cloth hanging downward.

are rectangular slots, formed in the lower jaw, and extending into the hole at its centre, these slots being provided for the reception of the pin e, upon which the lugs f f are pivoted, said pin projecting out from the surface of the lower or metal portion b of the handle A.

After the ends of the cloth are secured in place, the handle is revolved sufficiently to allow the pin e to drop into one of the rectangular slots i i, when the handle is drawn up and turned a quarter of a revolution, thus bringing the pin on the upper side of the lower jaw, and effectually locking the handle in place in a position ready to use the mop.

The handle is prevented from being drawn up out of the hole in the lower jaw by the two lugs f f being brought in contact therewith, the lugs being prevented from closing together sufficiently to be drawn through by one of them coming against a shoulder, k, formed on the other.

After the mop has been used, and the cloth is saturated with water, it may be wrung out in an extremely convenient and ready manner, as follows:

The handle is revolved so as to liberate its pin e from the lower jaw, when the handle is allowed to slide down until its lugs f f are brought against the bight of the cloth, when, by the application of slight pressure and revolving the handle, the cloth is twisted tightly around, and the water within it is ejected therefrom.

The sides l of the upper jaw are flattened out, to allow of its being more conveniently grasped when the handle is turned.

In wringing the cloth, either the handle only or the upper jaw may be turned, or both may be turned simultaneously in contrary directions.

A mop composed of any material may be used in connection with my sliding and revolving handle.

When cotton-waste, or other similar loose material is to be used, it is necessary first to attach a binding to its bight, in order that the lugs may be enabled to retain hold of it while being twisted.

To prevent the pin *e* from catching into the mop-cloth, and obstructing the operation of the handle, I intend to provide an aperture on the upper side of the lower jaw, in which the pin *e* may snugly fit flush with its surface.

Claim.

What I claim as my invention, and desire to secure by Letters Patent, is—

The sliding and revolving handle *A*, with the device for locking it in place, and the device for catching the mop-cloth, in combination with the jaws *B C*, substantially as and for the purpose described.

JOHN A. WRIGHT.
